UNITED STATES PATENT OFFICE.

CARL AUGUST PFENNING, OF BARMEN, GERMANY.

MUSTARD-POT.

SPECIFICATION forming part of Letters Patent No. 500,035, dated June 20, 1893.

Application filed March 2, 1893. Serial No. 464,420. (No model.) Patented in Germany July 2, 1889, No. 51,390.

To all whom it may concern:

Be it known that I, CARL AUGUST PFENNING, a subject of the King of Prussia, residing at Barmen Rittershausen, in the Province 5 of Rhenish Prussia, Kingdom of Prussia, German Empire, have invented new and useful Improvements in Mustard-Pots, of which the following is a specification.

This invention relates to a mustard pot in which the contents are thoroughly inclosed and from which they are automatically forced by a piston, whereby a dripping of the contents from the outlet after use is wholly avoided and for which I have obtained Letters Patent from the German Empire No. 51,390, dated July 2, 1889.

This invention is set forth in the following specification and claims and illustrated in the annexed drawings, in which—

20 Figure 1, is a vertical section along A B Fig. 3. Fig. 2, is a front elevation of the pot. Fig. 3, is a horizontal section of the pot along C D Fig. 1. Figs. 4 and 5, show a modification.

25 The pot or receptacle *g* of porcelain, stone ware or the like is provided with the outlet *a* and with a piston *k*, tightened by a ring or packing *r* and guided by tube *o* extending upward through cover *d*. In the tube *o* which 30 is suitably tapped or threaded at its upper part, turns the screw *s* having handle *i* for actuating the screw to raise or lower the piston. The piston and screw are supported by spring *f* braced or inserted between the cover *d* and the plate *p* secured to the screw. Said 35 plate *p* has a projection *v* engaging a corresponding depression in another plate *p'* removably placed into the top of shell *h* formed integral with the cover. The piston *k* can be

40 provided at its under face with a porcelain or stone ware plate and is prevented from turning by the stem *t* extending through the cover and serving also as an indicator to show the position of the piston. I do not, however, confine myself to the employment of the stem *t* for preventing the piston from turning, as 45 obviously this result may be otherwise accomplished. The descent of the piston is caused by turning the screw *s* in the proper direction, such descent being caused by the projection *v* moving out of the recess in plate

p' while at the same time the screw thread forces the piston down. At the end of a half turn however the piston moves upward or back in consequence of the projection *v* snapping back into its seat or recess in plate *p'*. In consequence of said movement of the piston acting on the contents a half turn of the screw will cause a certain quantity of the contents to pass out through opening *a*. At 60 the end of the half turn, that is to say, as soon as the projection *v* snaps into the depression in plate *p'*, the retreat of the piston will correspondingly draw or suck back the contents so that all after-dripping from the outlet is 65 prevented since the mass contained in the outlet correspondingly recedes on the short retreat of the piston.

The operation of the parts is such that when the screw *s* is turned in its screw-socket 70 connection with the piston to advance the latter, the spring *f*, projection *v*, and the depression in the plate *p'* constitute means whereby successive or intermittent retractile movements are imparted to the piston while 75 the screw *s* is being turned to advance said piston.

This arrangement enables a certain quantity of the contents to be forced out of the receptacle by giving the screw a half turn or a 80 less turn according to the number of depressions in plate *p'*. If for example as shown in Fig. 4 in section and in Fig. 5 in plan view the engaging plates *p* and *p'* are provided with four teeth, each quarter turn will cause 85 the piston to advance and snap back. These toothed plates have the teeth inclined toward each side so that the screw can also be turned in the reverse direction to screw up the piston.

To prevent rotation of the upper plate it is 90 provided with a depression engaged by a rib on cap *m*. The lower plate is attached to the screw so as to turn therewith. The cover *d* is fastened by straps or catches *ll* engaging the lugs *n*. On swinging back or disengaging 95 the fastenings *l* the cover is free to be removed. The cover can however be secured to the receptacle in any other suitable well known way.

By the above described, automatically operating arrangement which furnishes only a 100 definite quantity for present use, the con-

tents are protected against air, dust and the like so that they can be preserved in the receptacle for a long time in serviceable condition.

5. What I claim as new, and desire to secure by Letters Patent, is—

1. The combination with a pot or receptacle, having an outlet, of a piston arranged in the pot or receptacle, a rotary screw, having a screw-socket connection with the piston for advancing the latter as the screw rotates, and means for slightly retracting the piston at intervals as the screw is rotated to advance the piston, substantially as described.

15. 2. The combination with a mustard pot, having a plate provided with a recess, and a piston arranged in the pot for expelling the contents thereof, of a screw for advancing the piston, a spring-pressed plate secured to the screw, and having a projection *v* which alternately passes out of and into the aforesaid

recess as the screw is rotated to advance the piston, substantially as described.

3. The combination with a mustard pot, having a shell *h*, provided at its upper end with a recessed plate *p'*, of a piston *k* for expelling the contents of the pot, a screw *s* for advancing the piston, a plate *p* secured to the screw, and having a projection *v* which alternately passes out of and into the recess in the plate *p* at the upper end part of the said shell, and a spring *f* located in the shell and acting upon the plate secured to the screw, substantially as described.

In testimony whereof I have hereunto set my hand in the presence of two subscribing witnesses.

CARL AUGUST PFENNING.
